Karl Ladisch,

By *Henry M. Gandy* Atty.

UNITED STATES PATENT OFFICE.

KARL LADISCH, OF MEISSEN, GERMANY.

DRIER.

1,416,960.

Specification of Letters Patent.

Patented May 23, 1922.

Application filed August 15, 1921. Serial No. 492,582.

To all whom it may concern:

Be it known that I, KARL LADISCH, a citizen of the German Republic, residing at 3 Luisenplatz, Meissen, Germany, have invented certain new and useful Improvements in Driers; and I do hereby declare the following to be a full, clear, and exact description of the invention, such as will enable others skilled in the art to which it appertains to make and use the same, (for which applications have been filed in Germany January 27, 1916; France April 12, 1920; Italy April 13, 1920; Czecho-Slovakia December 13, 1919, and Poland February 27, 1920,) reference being had to the accompanying drawings, and to letters or figures of reference marked thereon, which form a part of this specification.

My invention relates to driers for sliced vegetables, such as turnips, beets, potatoes, and other materials to be dried.

The invention comprises a heating drum having on its outside blades inclined to the axis of the drum, said drum having perforations through which the hot air or drying gases pass, the drying medium being supplied to the interior of the drum at one end. The drying medium passes through the perforations in the drum, and dries the material that is gradually forwarded from the supply end of the drum to the opposite discharge end thereof.

In order to distribute the drying medium, hot air or furnace gases, so that there shall be supplied a greater quantity at that end of the drum that received the fresh material to be dried than at that portion having the material which has been partially dried and forwarded but part way to the discharge end, the drum is provided with an internal distributor tube, comprising connected sections adjustably spaced apart. This tube is so made that the spaces between the sections progressively increase in width from the discharge end to the feed end. The space between this tube and the interior wall of the heating drum is divided by annular partitions into a plurality of chambers.

Referring to the drawings in which like parts are similarly designated—

Figure 1 is a vertical longitudinal section of the drying device.

Fig. 2 is a cross-section, and

Fig. 3 is a detail view of one of the devices for adjusting the spaces between the tube sections.

Fig. 4 is a detail view of a modification.

The drier comprises a stationary casing *f* having an inlet *g* for the material to be dried, a discharge opening *z* for the dried material, and an exhaust *m* for connection, as customary, with an exhaust fan. The casing has a circular bottom 2, Fig. 2, and is provided with end walls 3 and 4.

The heating drum *c* is provided on its ends with stiffening end members *c'* and *c''*, having flanges 5 and 6, respectively. These end members support the drum *c* and in turn are supported on rollers 7 on frame members 8 of the drier.

The drum *c* or rather that portion included between the end walls 3 and 4, is provided on its exterior with a well-known arrangement of forwarding blades 9, inclined to the axis of the drum, the arrangement being such as to forward the material gradually from the inlet end to the discharge end (left to right).

That portion of the drum *c* lying between the end walls 3 and 4 is provided with perforations 10 for the passage of hot air or furnace gases.

The drying medium, hot air or furnace gases, is supplied to the drum through a stationary inlet pipe *p* the end of which enters 85 a flange 11 on the flange 6. This flange 11 covers the joint between said pipe and a distributing pipe composed of spaced sections *a*—*a'* so connected together that there are formed between the adjacent sections 90 spaces *b*'—*b*" increasing in width from the discharge end to the inlet end of the drum.

The sections are connected together in spaced relation by straps 13 and are supported from the drying drum *c* by means of 95 brackets 12 and partition rings *d'*, *d*², *d*³, and may be adjustably connected one to the other by adjustable connections of any suitable type or as hereinbefore described, so that the spaces *b*'—*b*" may be adjusted in 100 width; the arrangement of the partitions *d'* *d*², *d*³ being such that the chambers *e'*—*e*⁴ are formed between the distributing drum and the heating drum, and the spaces are so arranged in progressively increasing 105 widths that the chamber *e*⁴ receives the greatest quantity of the drying medium.

The adjustment of the width of the spaces *b*'—*b*" can be effected, as shown in Fig. 3, by screw bolts 20, rotatably arranged in 110 bearings 21 of one section and engaging into nuts 23, fastened to the next section. By

turning these screws the sections can be adjusted, so that the spaces between the sections become greater or smaller. This adjustment is for the purpose of controlling the amount of gases supplied to the heating chambers $e'-e^4$ and thereby controlling the quantity of drying medium supplied through the perforations 10 to the material on the drum, according to the rate of drying, for particular material, or according to the distribution of the drying medium desired.

Instead of spaces, the distributing drum may be provided with perforations r as shown in Fig. 4 arranged in circular rows spaced apart the same as the spaces shown. These perforations can be closed more or less by dampers or slides s , which can slide on the drum and can be moved by rods t , provided with screws u , engaging flanges v of the dampers s .

The end of the last distributor section a^8 is provided with a valve k which can be moved back and forth by a hand wheel on a rod l mounted in the head h closing the end of the drum.

In order to cool the entrance end of the heating drum c , where the wet raw material is fed, the head h is provided with openings i controlled by doors or dampers r of any construction desired, so that the cool outside air may be admitted to prevent the sticking of the material, or cooking of the starch contained in it. When the valve k is withdrawn from the end of section a^8 , cool air coming through the head of the drum is admitted to the distributor tube as well as to the chamber e^4 through the space between the last distributor section a^8 and the heating drum c . The valve k when moved inward controls the amount of drying medium admitted to chamber e^4 , while the dampers or slides r controlling the openings i regulate the amount of cold air admitted to the chamber or to the perforations between the partition d^8 and wall 3, whereby the drying in the initial stage takes place without liquefying or caramelizing the starch in the substances being dried, after which hotter gases act upon the material without changing the starch content, to rapidly complete the drying.

The drum and tube are rotated by a driven

pinion o gearing with a circular rack n on the drum.

I claim:

1. In a drier, a rotatable perforated heating drum, in combination with a distributor tube within said drum and spaced from the walls thereof said tube having spaced openings therein increasing in size from the discharge end to the inlet end of said drum.

2. In a drier, a rotatable perforated heating drum, in combination with a distributor tube within said drum and spaced from the walls thereof, said tube having spaced openings therein increasing in size from the discharge end to the inlet end of said drum, and means for adjusting the size of the openings in the distributor tube.

3. In a drier, a rotatable perforated heating drum, in combination with a concentric distributor tube therein spaced from said drum, said tube composed of a number of spaced sections, and means to adjustably secure the sections together to vary the width of said spaces.

4. In a drier, a rotatable perforated heating drum, in combination with a concentric distributor tube therein spaced from said drum, said tube composed of a number of spaced sections, and means to adjustably secure the sections together to vary the width of said spaces, and annular partitions dividing the space between said drum and tube into separate chambers receiving drying medium from one or more spaces between sections of said tube.

5. In a drier, a rotatable perforated heating drum, in combination with a concentric distributor tube within said drum and spaced therefrom, annular partitions dividing the space between said tube and drum into separate chambers, said tube having one or more openings discharging into each chamber and the openings increasing in size from the discharge end to the inlet end, a valve controlling the end of said tube and means to admit cold air through the end of said drum into the chamber adjacent the inlet end of the drier.

In testimony that I claim the foregoing as my invention, I have signed my name.

KARL LADISCH.
